STOP AND TURN SIGNAL

Fusajiro Mamiya, Los Angeles, Calif.

Application July 5, 1933, Serial No. 679,058

4 Claims. (Cl. 116—39)

The present invention relates to automobile stop and turn signals of the type forming the subject matter of my previous application, Serial Number 668,323, filed April 28, 1933, and more particularly has to do with improvements in the fluid operated actuator therefor.

An object of this invention is to provide a fluid operated actuator of comparatively simple, compact and inexpensive form which will be reliable in operation and insure an accurate and effective performance of the signal at all times.

Another object is to provide in a signal actuator such as described a novel and efficient means for controlling the operation of the actuator in such manner that any one of the various signals may be displayed at the will of the operator.

A further object is to provide an actuator such as described which is characterized by a novel automatic atmospheric air intake valve operating to admit atmospheric pressure fluid to the working cylinder in such manner as to simplify and render more reliable the control valve as well as the signal device as a whole.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Fig. 1 is a vertical sectional view of the signal and actuator of this invention;

Fig. 2 is a sectional view taken on the plane of line 2—2 of Fig. 1;

Fig. 3 is a vertical sectional view of the control valve;

Fig. 4 is a schematic view of the actuator and control means therefor;

Fig. 5 is a fragmentary perspective view showing the signal of this invention as when installed on an automobile.

One embodiment of the present invention, as shown in detail in the accompanying drawings, comprises a semaphore type signal A adapted to be secured on an automobile B, as shown in Fig. 5, by means of bracket C and which is operated by the fluid pressure actuator D. This actuator is connected with the intake manifold of the automobile engine, (both of which latter are not shown) in any well known manner and is controlled by a manually operated valve E mounted on the steering column F and by an

automatic air admission valve G. It should be here noted that the valve G is carried by the piston H of the actuator, as may be seen with reference to Figs. 1 and 4.

The semaphore signal here shown is comprised of a casing 6 carried by the bracket C, a semaphore signal arm 7 arranged to swing into and out of the casing and bearing plates 8 rotatably supporting the semaphore and in turn supported by the actuator D. The actuator D includes a cylinder 9 which is supported by the casing 6 and bracket C, the plates 8 being secured to opposite sides of the cylinder. Extending from the piston H out through a stuffing box 10 is a tubular rack bar-piston rod 11 which meshes with a gear 12 on the semaphore 7 whereby to actuate the latter upon movement of said piston.

The actuator D is designed to be operated by fluid pressure and as here shown is adapted to be connected with the intake manifold of the automobile engine by means of a pipe line 13 leading to the control valve E, and a pipe line or lines generally indicated by the numeral 14 which connects the valve E with the cylinder 9. Inasmuch as the movement of the piston H is effected and controlled by a differential in fluid pressures, provision is made for creating in different parts of the cylinder, at will, atmospheric or sub-atmospheric pressures. Strictly speaking there are three independent ways of creating atmospheric pressures in said cylinder, to wit; through the control valve E; by contemplated leaking into cylinder 6 through the stuffing box 10, and through the tubular piston rod 11 and valve G. Creation of the sub-atmospheric pressure, as will be noted, is effected by the suction or vacuum force of the engine through the valve E and its connection with the engine and said actuator.

When the semaphore is in non-signalling position, the piston H is maintained in its uppermost position. To make a "stop" signal the operator turns the handle 15 of the valve E to bring the rotary valve plate 17 which is connected to the handle by the drive elements 18 and 19, into the position shown in Fig. 4. In such position the radially extended groove 20 of said valve plate registers at its outer end with a port 21 formed in a stationary valve plate 22. It should be noted that the suction pipe line 13 is connected to a port 23 in the plate 22 and said port at all times is in registration with the groove 20. The valve plate 17 has a pin and slot connection indicated at 17' in Fig. 4, with the plate 22 whereby to guide the plate 17 in the turning thereof.

One of the lines 14 leads from port 21 to a

port 23' in the cylinder 9. As the piston H being above the port 23' when the foregoing valve operation is effected, the portion of the cylinder below the piston will be evacuated and a sub-atmospheric pressure created in said portion by the ensuing suction action. To move the piston it is necessary to create a pressure above it, and in this instance atmospheric air is caused to enter the space above the piston, through the passage 10 24 in the tubular piston rod 11. Before, however, air may enter the cylinder in this manner the valve G must be opened. This valve includes two balls 25 and 26 in a passage 27 which extends vertically through the piston H, it being noted 15 the piston has a reduced central appendage portion 28. The passage 27 is substantially L-shaped and the horizontal portion thereof communicates with the rod passage 24, through a short passage 30. Ball 25 operates against a seat 20 31 to control the discharge of air below the piston, whereas ball 26 operates against a seat 32 to control the discharge of air through the vertical leg of the passage 27 into the space above 25 the piston.

25 As soon as the portion of the cylinder below the piston becomes evacuated the ball 25 is forced against its seat 31 by the pressure of the atmospheric air admitted behind said ball through 30 passage 24. The ball 26 simultaneously moves away from the seat 32 and opens passage 27 leading above the piston and atmospheric air therefore enters the upper part of the cylinder whereby to move the piston downwardly. It 35 should be noted, that the stuffing box 10 will leak sufficient to permit atmospheric air to enter the upper part of cylinder 9 whereby to act upon the ball 26 and permit the latter to open as aforesaid.

40 Upon downward movement of the piston to the extent shown in Fig. 4 the port 23' is covered by the piston and the evacuation of the cylinder ceases whereupon the operative pressure fluid above the piston becomes ineffective to move the piston. Such movement of the piston moves 45 the semaphore into the standard "stop" signal position indicated in Fig. 1.

When it is desired to move the semaphore into horizontal or left turn position either from the non-signalling or stop signal position, the valve 50 handle is moved to bring port groove 20 of plate 11 into registration with a port 36 in plate 22 which port through one of the pipe lines 14 is connected with the port 37 in the cylinder 9. This again causes the cylinder below the piston 55 to be evacuated and the valve G again goes through the cycle of operation, as described hereinbefore, to permit the operating atmospheric pressure fluid to move the piston downward sufficient to move the semaphore into the said "left turn" position, the movement of the piston ceasing 60 when the piston covers said port 37.

When it is desired to move the semaphore into the upwardly inclined "right turn" signal position, the valve handle is turned to bring groove 20 65 of plate 11 into registration with port 38 in the plate 22 and the cylinder is again evacuated through port 39 and the valve G again operated until the bottom of the piston engages the bottom 70 of the cylinder. Although the evacuation action will continue as long as the valve remains in "right turn" position the piston cannot move past the position it reaches necessary to effect said signal, the port 39 being left uncovered in this 75 case, as said port must be open to admit the

operating fluid if the piston is to be moved into its other signal positions or back to non-signalling position.

To move the semaphore into non-signalling position from said right turn position the operator moves the valve to bring valve groove 20 5 into registration with port 40 in plate 22 and the portion of the cylinder above the piston is evacuated through port 41 and one of the lines 14. Valve G now reverses its operation as ball 10 26 is closed by the atmospheric pressure behind it and the negative pressure in said upper part of the cylinder, whereas due to air entering the cylinder through port 43, pin hole port 42 in valve plate 17, port 38, one of the pipe lines 14, and 15 cylinder port 39, the ball 25 will drop away from its seat 31 and open the passage 27. Atmospheric air now enters the portion of the cylinder below piston H and operates to move said piston upward whereby to swing the semaphore back into 20 the casing therefor. As the semaphore strikes the side of cylinder 9 (see Fig. 1), the movement of the piston is stopped with the port 41 remaining uncovered by the piston, whereby the evacuation of the cylinder will continue and 25 thereby hold the piston and semaphore against unintentional movement.

It should be noted that the piston may be operated in either direction when the signal is in "stop" and "left turn" positions and, in all cases 30 of upward movement of the piston the portion of the cylinder below the piston will be vented to the atmosphere through pin hole 42 which, it is noted, will always register with the space below the piston while the passage or groove 20 35 is registered with port 40 which will evacuate the cylinder above the piston.

It will now be apparent that the apparatus of this invention will provide the advantages and 40 objects hereof in a particularly efficient manner.

I claim:

1. In a traffic signal, a movable signal member, a cylinder having ports therein, a piston in said cylinder arranged to cover and uncover certain of said ports, means of operative connection between said piston and said signal member including a piston rod having an atmospheric air intake passage, said piston having a passage therein communicating with said intake passage and opening on the upper and lower sides of the piston, said piston passage having a portion thereof horizontally disposed and provided with opposed valve seats, valve means in said piston passage controlling the entrance of atmospheric air into the cylinder, and means operative 45 through said ports for creating a differential in fluid pressures in said cylinder, said valve means comprising two ball valves located in said horizontal portion of said passage and cooperating with said seats, which latter are on opposite sides 50 of the point of communication of the piston passage with the rod passage.

2. In a traffic signal, a movable signal member, a cylinder having ports therein, a piston in said cylinder arranged to cover and uncover certain of said ports, means of operative connection between said piston and said signal member including a piston rod having an atmospheric air intake passage, said piston having a passage therein communicating with said intake passage and opening on the upper and lower sides of the piston, valve means in said piston passage controlling the entrance of atmospheric air into the cylinder, and means for creating sub-atmospheric pressures in said cylinder selectively through any 65 70 75

one of said ports, including means operating to maintain a sub-atmospheric pressure above the piston when the signal member is in non-signalling position, at which time said valve means permits atmospheric air to enter the lower part of the cylinder, through the rod and piston passages.

3. In a signal, a casing, an actuator mounted therein, bearing plates fixed to and extending upwardly from said actuator, a semaphore arm rotatably supported by said plates, and means of operative connection between the semaphore and said actuator.

4. In a signal, a movable signal member, a cylinder having ports spaced apart lengthwise thereof, a piston reciprocatingly mounted in said cylinder and arranged to open and close certain of said ports during movement thereof, means of operative connection between said signal member and said piston, a valve casing, a stationary valve plate in said casing having ports corresponding

in number to those of the cylinder conduits joining the cylinder ports with the valve ports, said plate having a suction port therein, a conduit for connecting said suction port with the intake manifold of an internal combustion engine, a rotary valve plate engaged upon the first named plate and having a groove therein disposed to be selectively registered with the valve ports and at all times in registration with the suction port, said means of operative connection including a piston rod having an atmospheric air intake passage therein, said piston having a passage therein registering between its ends with said piston rod passage and opening at its ends upon opposite sides of said piston, and a check valve in said piston passage, said rotor plate having an atmospheric air intake opening therein arranged to register with certain of said stationary valve plate ports.

FUSAJIRO MAMIYA.
